CONTROL DEVICE FOR HYDRAULIC LINES

Garold A. Kane, Minneapolis, Minn., assignor to
 Northern Pump Company, Minneapolis, Minn.,
 a corporation of Minnesota

Application February 23, 1940, Serial No. 320,392

14 Claims. (Cl. 137—53)

This invention relates to a device for controlling the flow of liquid between two lines or conduits containing liquid under pressure. Liquid is often supplied by one line under pressure to some form of apparatus actuated by said liquid or the liquid is placed under pressure in a line by some form of apparatus such as a pump. In all of such cases there is, of course, a line having a liquid therein at lower pressure to which the liquid is supplied or into which it is exhausted or discharged. It is frequently desirable to limit the pressure at which the liquid is supplied and to open means leading to the exhaust or discharge line when the pressure reaches a certain point.

It is an object of this invention to provide a simple and efficient device for controlling the flow of liquid between two lines in accordance with the pressure developed.

It is a further object of the invention to provide a simple and efficient device for controlling the flow of liquid from one line or conduit containing liquid under pressure to a line or conduit containing liquid under lesser pressure, which device is operated by the liquid in accordance with the pressure developed and one in which there is a negligible leakage before the main operation thereof.

It is another object of the invention to provide a device such as set forth in the preceding paragraph including a control passage having ports of considerable size opening thereto, which ports are controlled by a control valve or pilot valve to cause operation of the device, said ports of considerable size insuring that there will be no clogging of the device by dirt or other foreign material.

It is also an object of the invention to provide such a device as above set forth having means for varying the pressure at which it will operate.

It is still another object of the invention to provide a device for controlling the flow of liquid from one line containing liquid under pressure to another line containing liquid under pressure comprising a duplex device including a member having a relief passage with valves at either end thereof similarly related to the lines of high and low pressure respectively with a control valve and passages disposed symmetrically to said valves with adjustable means for determining the pressure at which the device will operate so that it can be used for limiting the pressure on either line, said means being differentially set for the desired operating pressures.

It is further an object of the invention to pro-

vide a device controlling the flow of liquid from one line containing liquid under pressure to another line containing liquid under lesser pressure comprising a member having a relief passage, a valve normally closing said passage adapted to be operated by the pressure of the liquid and a control valve to which is applied the full pressure of said first mentioned line, said control valve being operated upon a predetermined pressure to cause opening of said first mentioned valve.

These and other objects and advantages of the invention will be fully set forth in the following description made in connection with the accompanying drawing in which like reference characters refer to similar parts throughout the several views and in which:

Fig. 1 is a vertical longitudinal section through the device taken on different planes.

Referring to the drawing, a member designated generally as 10 is shown, the same having therein a passage 10a which will be referred to as a relief passage. Said passage 10a has valve seats 10b and 10c formed at the ends thereof and valve seat 10b is arranged to be engaged by a valve 11 having a portion formed on its end of frustoconical form adapted to closely engage seat 10b. Seat 10c is engaged by a similar valve 12. Valve 11 has associated therewith a plunger 11a. While plunger 11a could be connected with valve 11 in various ways, in the embodiment of the invention illustrated it is shown as an integral part of said valve. Plunger 11a fits in and moves in a cylindrical bore or chamber 10d formed in member 10. Valve 12 has a similar plunger 12a associated therewith which fits in and slides in a cylindrical bore or chamber 10e. Plunger 11a has a cylindrical projection 11b at the side opposite valve 11, which projection is surrounded by one end of a compression coiled spring 13, the other end of which surrounds a projection 14a on the end of a closing member or gland 14 having cylindrical portions seated in counterbores in the end of member 10. Member 14 will preferably be held in place by a plurality of circumferentially spaced bolts 15 extending through the same adjacent its outer edge and being threaded into member 10. A gasket 16 is shown disposed between member 14 and member 10. Plunger 12a has a projection 12b at the side opposite valve 12 which is surrounded by one end of a coiled compression spring 17, the other end of which surrounds a projection 18a on a closing member or gland 18 having cylindrical portions seated in counterbores in one end of member 10, which member

will be preferably held in place by bolts 19 extending therethrough adjacent its outer edge and threaded into member 10. A gasket 18b is disposed between member 18 and member 10. It will be seen that springs 13 and 17 act on valves 11 and 12 or plungers 11a and 12a tending to hold said valves to their seats. A control passage 10f is formed in member 10 preferably above passages 10d and 10e and while this passage might be of various forms, in the embodiment of the invention illustrated it is shown as cylindrical. Passage 10f communicates at its ends with other bores or passages 10g and 10h shown as of slightly larger diameter than passage 10f, thus forming shoulders and plunger disks 20 and 21 are disposed and fit respectively in passages 10g and 10h and normally engage the shoulders at the ends thereof adjacent passage 10f. Plunger disks 20 and 21 are engaged respectively by compression coiled springs 22 and 23, the other ends of which respectively engage plunger disks 24 and 25 also fitting in and slideable in passages 10g and 10h respectively. Passages 10g and 10h are threaded at their outer ends and have screwed or threaded thereinto the ends of closing members or glands 26 and 27 respectively. Members 26 and 27 have shouldered portions of different diameters thereon, the ones of smallest diameters being disposed in counterbores in member 10 and having their ends engaging gaskets 28 at the bottoms of said counterbores. The shouldered portions of largest diameter engage gaskets 29 contacting the outer ends of member 10 and having portions extending at right angles thereto, one of which overlies the upper portions of members 26 and 27 respectively and the lower portions of which are seated in small recesses formed in the ends of member 10. Members 26 and 27 have reduced and exteriorly threaded outer portions on which are threaded closed cylindrical caps 30, the ends of which engage gaskets 31 disposed between the same and members 26 and 27 respectively. Members 30 preferably will have part of their periphery of angular formation so as to conveniently receive a wrench. Members 26 and 27 are centrally bored and threaded to receive threaded and headed screws 32 having reduced and pointed inner ends seated in small conical recesses in the plunger disks 24 and 25 respectively. Jamb nuts 33 are disposed on screws 32 and engage the outer ends respectively of members 26 and 27. It will be noted as shown on the drawing that the ends of screws 32 are disposed within caps 30. A valve member designated generally as 34 is disposed in control passage 10f, which valve may be called a pilot valve or control valve. Valve 34 comprises a central reduced rodlike portion having ends which normally as illustrated engage disks 20 and 21. Said valve also has spaced portions or lands 34a, 34b and 34c. Land 34a controls a port formed by a passage 10i extending from passage 10f to relief passage 10a. Another passage 10j extends from chamber 10d toward passage 10f and has spaced passages 10j¹ and 10j² forming ports opening into control passage 10f. Another passage 10k extends from chamber 10e toward passage 10f and has spaced passages 10k¹ and 10k² forming ports opening into control passage 10f. Another passage 10m has a port opening into passage 10f and extends therefrom through member 10 to chamber 10d at one side of plunger 11a which is the side opposite valve 11. A similar passage 10n has a port opening into passage 10f and extends through

member 10 to the passage 10e at one side of plunger 12a which is the side opposite valve 12. A conduit 35 is connected to member 10 communicating with chamber 10d at the side of plunger 11a on which valve 11 is disposed. Annular grooves 10o and 10p are disposed opposite the ports of passages 10j², 10k¹ and 10m to equalize the pressure on valve portions 34c, 34b and 34a. Conduit 35 will connect with the line or 5 conduit 36 carrying the liquid with the higher pressure. Another conduit 37 is connected to member 10 and communicates with chamber 10e at the side of plunger 12a on which valve 12 is disposed. Conduit 37 connects with another conduit or line 38 which will contain the liquid under the lesser pressure which is usually the exhaust or discharge conduit. For more convenient reference the chamber in bore 10d at the side of plunger 11a on which valve 11 is disposed will 10 be referred to as chamber 10d¹ while the chamber at the opposite side of said plunger will be referred to as chamber 10d². The chamber at one side of plunger 12a will be referred to as 10e¹ while the chamber at the opposite side which contains spring 17 will be referred to as 15 chamber 10e². The operation of the device is as follows: Let it be assumed that liquid is supplied for any purpose in conduit 36 at considerable pressure. This liquid after passing through some apparatus or being used for some purpose is discharged into conduit 38 at a lower pressure. It 20 is desired to limit the pressure in conduit 36 or to provide a certain differential between the two lines 36 and 38. The spring 23 will be set so that it will yield and plunger 21 will be moved upon the attainment of a predetermined pressure. This pressure, of course, can be varied as desired by operation of the screw 32 which will 25 compress spring 22 to give the desired pressure. With the parts in the normal position shown the high pressure from line 36 will be transmitted through pipe 35 to chamber 10d¹. This pressure will be transmitted from chamber 10d¹ to passage 10j¹ and passages 10j¹ and 10j² to control 30 chamber 10f at both sides of valve portion 34c. The pressure will thus be transmitted through passage 10m from the chamber at the right of portion 34c to chamber 10d². This high pressure therefore acts upon the large area at the outer side of plunger 11a and said plunger is held in position to keep valve 11 closed with its end against seat 10b. It will likewise be seen that the lower pressure from line 38 will be transmitted through conduit 37 to chamber 10e¹. This 35 pressure will be transmitted through passage 10k, its branches 10k¹ and 10k² and their ports to control passage 10f at both sides of valve portion 34b. This pressure will also be transmitted from the left hand side of portion 34b through passage 10n to chamber 10e². There is thus the same pressure at both sides of plunger 12a and this pressure acting against the large outer side of said plunger will hold valve 12 in closed position with its end against seat 10c. Valve 12 is also held closed by spring 13. Springs 13 and 17 are of fairly light construction. When the predetermined pressure is reached at which it is desired to have the device operate, the pressure upon the left hand ends of portion 34c of valve 34 will cause said valve to move to the right and compress spring 23 by movement of plunger disk 21. This causes valve portion 34c to move so that it will close the port of passage 10j². When this 40 port is closed the high pressure supplied between

valve portions 34c and 34a is cut off. As valve 34 moves to the right valve portion or land 34a will open the port of passage 10i. When this happens passage 10m is connected to relief passage 10a. Pressure is now relieved or reduced in chamber 10d² and the high pressure which is maintained in chamber 10d¹ will move plunger 11a to the left, thus opening valve 11. This will permit the liquid from chamber 10d¹ to flow into relief passage 10a and this liquid being at much higher pressure than the liquid in chamber 10e¹, valve 12 will be opened against the pressure of light spring 17 and the liquid can flow directly to the low pressure line 38. The device is used with pressures which are quite high and is often used where the liquid pumped is oil. It has been a problem of prior devices to prevent leakage when the pressure became high and approached the relief point. With the present construction the valve portions 34c and 34a are so arranged with ports from passages 10j² and 10i that the portion 34a is just opening passage 10i as passage 10j² is closed by portion 34c. No leakage can thus occur until just at the point when the device operates. This interval in which any leakage might possibly occur is so small as to be negligible. In practice it has been found that valve 11 is held constantly and quietly at the necessary fixed distance from seat 10b to maintain the desired pressure. In some prior devices there was a tendency for this valve to pound or vibrate. It is pointed out that even if some liquid should leak past valve 11 it will pass into relief passage 10a. As the leakage continues the pressure will build up in passage 10a and when it gets to a point much above the pressure in chamber 10e¹ and 10e² it will move valve 12 and merely pass out into the low pressure line. It will be noted that the device is symmetrical and that valve portion 34a is normally centrally disposed over the port of passage 10i. Portions 34b and 34c are symmetrical with relation to the ports adjacent the same. The device can thus be used to control the pressure whether pipe 38 is the discharge or relief line or whether pipe 36 is the discharge or relief line. The device is thus a duplex device. The springs 23 and 22 can be set so as to be compressed at different pressures. For instance, spring 23 could be set so that the device will operate to permit passage of liquid to low pressure line 38 at 1000 pounds and spring 22 could be set so as to yield upon a pressure of 400 pounds so that liquid would be relieved into line 36 if line 38 were made the high pressure line.

Attention is also called to the fact that there are no small passages through which the liquid must pass in the operation of the device. The ports opening into control passage 10f are all of large size and there is no chance for dirt or foreign matter to accumulate and clog these passages, which action has occurred in devices having small passages or needle valve structures. It will also be seen that the device can be readily vented to remove all chance of any air accumulation or any adverse action by the accumulation of air. Since the device is, as stated, symmetrical and the parts at one side are identical with the parts at the other, it is believed that it will not be necessary to describe the operation should the relief line or the discharge or exhaust line be in conduit 36.

One important feature of the device is that the full pressure from the high pressure line 36 is applied to the valve 34. In devices of the prior art the liquid has had to pass through a small

opening and this throttles down the pressure. In such a case the full pressure of the high pressure line is not applied to the valve causing operation of the device. The present construction acts with greater precision and the device operates when the desired pressure is reached. The device will also operate to hold the pressure very close to the desired or predetermined pressure. It is also pointed out that when valve portion 34c closes the port of passage 10j² the pressure from the high pressure line is cut off from passage 10d². The same action would occur, of course, if the valve were operating the other way when portion 34b would close the port of passage 10k¹ and cut off the pressure from chamber 10e². Such action insures a positive opening of the valves 11 and 12 respectively.

From the above description it will be seen that I have provided a very simple and efficient control device for liquids under pressure and one which will function accurately and efficiently to relieve the liquid at a certain pressure. All parts are controlled by the pressure of the liquid and the device acts with great precision. As stated there is no appreciable period of leakage before the device operates and there are no small passages to become clogged with dirt or other foreign material and interfere with the operation. The device is exceedingly simple and compact and can be easily and inexpensively produced. The device requires little or no attention for maintenance. The same has been amply demonstrated in actual practice and found to be very successful and efficient.

It will, of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. A device for controlling the flow of liquid from one line containing liquid under pressure to another line containing liquid under lower pressure comprising a chamber having openings at opposite ends, valves closing said openings, plungers for operating said valves, a control passage, a relief port communicating with said control passage and leading to said chamber, pairs of ports leading respectively from said control passage at opposite sides of said first mentioned port, the ports of each pair having passages leading to opposite sides of said plungers respectively, a control valve in said control passage having a portion normally closing said first mentioned port and having portions spaced from said first mentioned portion forming chambers in said control passage with which said pairs of ports respectively communicate, ports at the other ends of said last mentioned portions respectively having passages connected to said first and second mentioned lines and yielding means at each end of said control valve holding the same in set position, said first mentioned portion of said control valve being normally disposed centrally over said first mentioned port and said other valve portions and ports being disposed symmetrically with respect to said first mentioned port.
2. The structure set forth in claim 1 and means for varying the pressure at which said means will yield whereby said means may be dif-

ferentially adjusted to control the pressure in either line used as the high pressure line.

3. A valve for relieving hydraulic pressure from one line containing liquid under pressure to another line containing liquid under lower pressure comprising a member having a relief passage therein, a valve closing said passage, a plunger associated with said valve, a chamber adjacent said passage at one side of said plunger to which said first mentioned line is connected, a second chamber at the opposite side of said plunger, a pilot valve having spaced portions thereon, a passage leading from said relief passage normally closed by one of said portions, spaced ports at either side of the other portion connected to a passage leading to said first mentioned chamber, a passage leading to said second chamber having a port disposed between said portions and thus communicating with said last mentioned passage and an adjustable yielding means holding said pilot valve in set position whereby pressure will pass from said first mentioned line to both sides of said plunger and will operate on one of said portions of said pilot valve to close said passage leading to said second chamber and open said port leading from said relief passage whereby said plunger will be operated to open said first mentioned valve.

4. A device for controlling the flow of liquid from one line containing liquid under pressure to another line containing liquid under lower pressure comprising a member having a relief passage therein, valves at opposite ends of said passage normally closing said passage, plungers associated with said valves respectively adapted to be acted upon by pressure at opposite sides thereof tending to open or close said valves, means connecting said first mentioned line to both sides of one of said plungers, means for connecting said other line to both sides of said other plunger, a control passage, a passage leading from said control passage to said relief passage and a control valve in said control passage having a land normally disposed centrally over and closing said last mentioned passage and having lands spaced from said land for controlling said two mentioned means respectively.

5. The structure set forth in claim 4, yielding means at each end of said control valve and means for varying the pressure at which said means will yield.

6. A device for relieving hydraulic pressure from one line containing liquid under pressure to another line containing liquid under lower pressure comprising a member having a relief passage therein, valves closing the ends of said relief passage, a pair of chambers adjacent each of said valves adapted to receive liquid under pressure for opening or closing said valves, a control chamber, a passage leading from said control chamber to said relief passage, passages leading from said control chamber at each side of said last mentioned passage to one of the chambers of each of said pairs respectively, passages leading from said control chamber spaced from said last mentioned passages respectively and leading to the other chambers of said pairs respectively and a control valve in said control chamber having a central portion controlling said second mentioned passage and having portions spaced therefrom for controlling said two last mentioned two sets of passages, said control valve being constructed and arranged to be operated upon the attainment of a predetermined pressure in said liquid in said first mentioned line.

7. The structure set forth in claim 6 and passages disposed at the remote ends of said last mentioned portions of said control valve through which the pressures from said lines respectively are transmitted to said control valve.

8. The structure set forth in claim 6 and yielding means disposed at each end of said control valve and means for independently varying the pressure at which said yielding means will yield to permit movement of said control valve.

9. A device for relieving hydraulic pressure from one line containing liquid under pressure to another line containing liquid under lower pressure comprising a member having a relief passage therein, valves closing the ends of said relief passage, a pair of chambers adjacent each of said valves respectively adapted to receive liquid under pressure for opening or closing said valves, a control chamber, a passage leading from said control chamber to said relief passage, passages leading from said control chamber and disposed equal distances at either side of said last mentioned passage and leading to one of each of said pairs of chambers respectively, passages spaced equally from said last mentioned passages respectively and leading from said control chamber to the other chamber of each of said pairs respectively, a control valve fitting in and movable in said control chamber having a central portion normally disposed centrally over said second mentioned passage and having portions spaced equal distances therefrom for controlling said last two mentioned sets of passages and means for applying the pressures of said lines respectively to said control valve at the remote ends of said last mentioned portions thereof and yielding means engaging the ends of said control valve, said passages from said control chamber being arranged symmetrically with respect to the center of said passage leading from said control passage to said relief passage.

10. A device for relieving hydraulic pressure from one line containing liquid under pressure to another line containing liquid under lower pressure comprising a member having a relief passage therein, valves closing opposite ends of said passage, a pair of chambers adjacent each of said valves adapted to receive liquid under pressure for opening or closing said valves, plungers in said chambers connected to said valves, a control chamber, a passage leading from said control chamber to said relief passage, passages leading from said control chamber at each side of said last mentioned passage to one of the chambers of each of said pairs respectively, passages leading from said control chamber spaced from said last mentioned passages respectively and leading to the other chambers of said pairs respectively and a control valve in said control chamber having a central portion controlling said second mentioned passage and having portions spaced therefrom for controlling said two last mentioned sets of passages, said two last mentioned sets of passages being symmetrically disposed at either side of and with respect to said second mentioned passage and said portions of said control valve being disposed symmetrically with respect to said central portion, said control valve being constructed and arranged to be operated upon the attainment of a predetermined pressure of said liquid in said first mentioned line.

11. A device for controlling the flow of liquid from one line containing liquid under pressure to another line containing liquid under lower pressure comprising a member having a relief

passage therein, a valve adapted to close said passage, a bore in said member, a plunger connected to said valve movable in said bore and forming chambers therein at opposite sides of said plunger, a passage leading from the chambers at the side of said plunger adjacent said valve to said first mentioned line, a control passage in said member, a control member movable therein having spaced lands, yielding means resisting movement of said control member in one direction, a passage leading from said last mentioned chamber and having branches with ports at either side of one of said lands in the normal position of said control member, a passage leading from said other chamber and having a port disposed between said lands in the normal position of said control member and a passage leading to said relief passage having a port covered by the other of said lands in the normal position of said control member.

12. A device for controlling the flow of liquid from one line containing liquid under pressure to another line containing liquid under lower pressure comprising a member having a relief passage therein, a pair of valves controlling the admission of liquid to said passage, plungers associated with said valves respectively having chambers at either side thereof and adapted to be moved by pressure of said liquid, passages connecting said lines respectively with one of the chambers of each of said plungers, a control passage spaced from said chambers, a passage leading from said relief passage and having a port communicating with said control passage, a control member in said control passage having a central land disposed centrally over said port in the normal position of said control member, yielding means resisting movement of said control member in opposite directions and passages leading from each of said chambers at opposite sides of said plungers respectively and having spaced ports communicating with said control passages at each side of said first mentioned port, said control member having lands spaced from said first mentioned land for controlling said last mentioned ports, said last mentioned ports being disposed symmetrically with relation to said first mentioned port and at opposite sides thereof.

13. A device for controlling the flow of liquid from one line containing liquid under pressure to another line containing liquid under low-

er pressure comprising a member having a relief passage arranged to be connected with said second mentioned line, a valve closing said relief passage, chambers adjacent said valve adapted to have liquid under pressure therein for closing or opening said valve, a control passage, means for connecting said first mentioned line to both of said chambers including a passage from one of said chambers to said control passage, a passage leading from said control passage to said relief passage, a control valve in said control passage movable upon a predetermined pressure of said liquid for opening said last mentioned passage and closing said second mentioned passage to cause a differential pressure in said chambers for opening said valve, and a third valve closing said relief passage acted on by liquid from said second mentioned line and adapted to be opened when said first mentioned valve is opened.

14. A device for controlling the flow of liquid from one line containing liquid under pressure to another line containing liquid under lower pressure comprising a member having a relief passage therein adapted to be connected to said second mentioned line, a valve closing said relief passage, a plunger associated with said valve adapted to be operated on by pressure at opposite sides to close or open said valve, a control passage, ports having passages within said member leading from said control passage to said relief passage and to opposite sides of said plunger respectively and a control valve in said control passage movable by liquid under pressure in said first mentioned line at a certain point and comprising spaced lands fitting said control passage to open said port leading to said relief passage and to close a port through which pressure from said first mentioned line is applied to one side of said plunger to cause movement of said plunger to open said first mentioned valve, said pressure being applied to one of said lands for moving said control valve, two of said lands of said control valve being arranged for closing and opening said ports respectively and so spaced that said port leading to said relief passage is opened just as said port leading to said one side of said plunger is closing whereby there is no appreciable period of leakage into said first mentioned port before said first mentioned valve opens to relieve the pressure.
